UNITED STATES PATENT OFFICE

172,521

LAMP BREAK

Edmond J. Spence, New York, N. Y., assignor to
Rembrandt Lamp Corporation, Chicago, Ill., a
corporation of Illinois

Application March 1, 1954, Serial No. 29,274

Term of patent 7 years

(Cl. D48—7)

To all whom it may concern:

Be it known that I, Edmond J. Spence, a citizen of the United States, and resident of New York, in the county of New York and State of New York, have invented a new, original, and ornamental Design for a Lamp Break, of which the following is a specification, reference being had to the accompanying drawings, forming a part hereof.

Fig. 1 is an elevational view of one side of a lamp break, embodying my new design, wherein the dotted line portion is for illustrative purposes only, to indicate an application of the break to a lamp;

Fig. 2 is an elevational view of one end as viewed from the right in Fig. 1;

Fig. 3 is an elevational view of the side opposite that shown in Fig. 1; and

Fig. 4 is a top plan view of the same.

I claim:

The ornamental design for a lamp break, substantially as shown and described.
